UNITED STATES PATENT OFFICE.

MARTIN WELLER, OF WAITSBURG, WASHINGTON.

ROTARY BRUSH.

1,231,825.

Specification of Letters Patent. Patented July 3, 1917.

Application filed October 28, 1916. Serial No. 128,238.

To all whom it may concern:

Be it known that I, MARTIN WELLER, a citizen of the United States, residing at Waitsburg, in the county of Walla Walla and State of Washington, have invented certain new and useful Improvements in Rotary Brushes, of which the following is a specification.

This invention relates to brushes which operate by a rotary movement, and its object is to provide a brush of this kind having a wide range of usefulness.

The invention also has for its object to provide a novel and improved means for driving the brush, and also to provide a means for feeding water to the brush and thus obtain a "fountain" brush.

Other objects and advantages of the invention will be pointed out in the detailed description appearing hereinafter, reference being had to the accompanying drawings forming a part of this specification.

In the drawings—

Figure 1 is a side elevation of the device, partly in section;

Fig. 2 is a similar view showing a slightly different arrangement of parts;

Fig. 3 is a plan view of a motor;

Figs. 4, 5 and 6 are plan views of certain parts of the device detached;

Fig. 7 is a plan view of another motor, and Fig. 8 is a cross section thereof, with its supporting shaft partly in section.

Referring specifically to the drawings, 10 35 denotes a casing which is preferably made of sheet metal, and has offsets to give it a neat appearance, and at the same time to provide internal annular shoulders 11, 12 and 13, respectively. The casing is open at 40 one end, and its other end is closed by a cover plate 14 held in place by a screw ring 15. A gasket 16 is placed on the shoulder 11 and the cover plate is clamped down on the gasket by the screw ring. The casing is 45 divided into three compartments indicated at 17, 18 and 19, respectively, the first mentioned being at the closed end, and the last mentioned at the open end, and the second mentioned in the middle.

50 In the end compartment 17 is located a rotary motor, which is a water wheel of any approved design, but preferably one of the impulse turbine type. The wheel is composed of spaced top and bottom plates 20 and 21, respectively, and vanes 22 therebetween. The wheel is fixed on a shaft 23

mounted in the center of the casing 10, the hub of the wheel being threaded to screw on a threaded portion 24 of the shaft, and down against a collar 25 on the latter. 60 The top and bottom plates guide the water against the perimeter of the wheel and confine it while passing therethrough, the bottom plate having openings 26 to allow a proper discharge from the wheel into the 65 middle compartment 18 of the casing. Directly beneath the bottom plate 21 of the water wheel is a ring 27 which seats on the shoulder 12. This ring extends inward as far as the periphery of the wheel and 70 thus compels the water to travel through the wheel and not to pass directly into the compartment 18.

The water inlet to the compartment 17 is 75 through the side thereof, the same having a nipple 28 to which a supply pipe 29 is connected, the latter being of such length that it may be used as a handle. The compartment 18 has a water outlet 30 in its side which may be closed by a plug 31; or a discharge pipe or hose 31^a may be attached thereto. Three outlets are preferably provided, one directly beneath the inlet 28, and the other two at right angles thereto. The two last mentioned openings 80 are provided in order that the water may readily escape, and to reduce the back pressure to a minimum. Without these additional outlets, when the work is such that the handle 29 is held horizontally, the casing 10 would naturally remain half full of water, which would be an impediment to the action of the water wheel.

In the end compartment 19 is mounted a 85 brush composed of a head 32 and bristle tufts 33. The brush is fixed on the shaft 23 by being screwed thereon as shown at 34 against a nut 35. A binding nut at the bottom may be provided if necessary. The brush tufts project a sufficient distance from 90 the open end of the casing to reach the surface to be operated on.

On the shoulder 13 seats a disk 36 having 95 openings 37. The disk also has a central opening through which the shaft 23 passes to provide a support or bearing for the latter. The shaft has a collar 38 resting on a bushing 39 supported by the center of the disk 36. The openings 37 are provided for the purpose of allowing the water to pass 100 and discharge on the brush. Should it be desired to use the brush dry, a solid plate or 114

disk 36^a will be placed on top of the disk 36, as shown in Fig. 2, to close the openings 37. This disk 36^a has a central opening to accommodate the bushing 39, and it may be made of metal, leather or any other suitable material. The bushing 39 also acts as a bearing for the shaft 23. When the disk 36^a is in place it serves as a gate to shut off the flow of water from the water wheel to the brush.

10 The brush head 32 has perforations 40 alternating with the tufts 33 to provide an ample waterway. It will be understood that the water passes through these perforations 15 to the brush tufts 33.

15 The shaft 23 is hollow and its upper end which is located in the compartment 17 has side openings 41. The end of the shaft to which the brush is attached is fitted with a 20 plug 42. Should it be desired to have only a small amount of water flow to the brush, the cover plate 36^a is inserted in place and the plug 42 is removed. The surplus water in the compartment 17 now enters the shaft 25 23 through the inlet openings 41 and runs down the inside of the shaft and is discharged into the center of the brush. By fitting a discharge pipe 31^a to the outlets 30 the excess water is conveniently carried 30 away.

When the brush is to be used for dusting, sweeping or other "dry" work, compressed air will be used for rotating it, a fan 44 being substituted for the water wheel. This 35 fan is shown in Figs. 7 and 8.

40 A bearing 45 for the upper end of the shaft 23 is a hollow nut which is screwed into the cover plate 14 and by which any wear may be taken up. Shims may be inserted in the nut if required.

45 While the preferred embodiment of the invention has been shown, it will be understood that various changes in the structural details may be made without a departure from the spirit and scope of the invention as claimed hereinafter. Different sizes and shapes of brushes and casings may be used, and the areas of the water passages may be varied to produce the best results.

50 The device has a wide range of usefulness, and it can be used for scrubbing, cleaning, dusting and sweeping automobiles, carriages, floors, windows, walls, ceilings, upholsterings, etc. It is therefore a general utility cleaner, and the rotary movement of the brush makes its work rapid and thorough.

I claim:

1. The combination of a casing open at one end and having a water inlet, a brush 60 in the casing and projecting from the open end thereof, said brush having a head which is provided with perforations, a water wheel in the casing, a shaft carrying the brush and the water wheel, the shaft being hollow and 65 having a water inlet opening into the casing

and a water outlet opening to the brush, and a removable gate between the water wheel and the brush head.

2. The combination of a casing open at one end and having a water inlet, a brush 70 in the casing and projecting from the open end thereof, said brush having a head which is provided with perforations, a water wheel in the casing, a shaft carrying the brush and the water wheel, the shaft being hollow and 75 having a water inlet opening into the casing and a water outlet opening to the brush, and a removable gate between the water wheel and the brush head.

80 3. The combination of a casing having a water inlet and a water outlet, a brush in the casing and projecting therefrom, said brush having a head which is provided with perforations, a water wheel in the casing between the aforesaid water inlet and outlet, a shaft carrying the brush and the water wheel, and a removable gate between the water outlet of the casing and the brush head, the aforesaid shaft being hollow and 85 having a water inlet opening into the casing and a water outlet opening through the brush.

4. The combination of a casing having a water inlet and a water outlet, a brush in the 90 casing and projecting therefrom, said brush having a head which is provided with perforations, a water wheel in the casing between the aforesaid water inlet and outlet, a shaft carrying the brush and the water wheel, a removable gate between the water outlet of the casing and the brush head, the aforesaid shaft being hollow and having a water inlet 95 opening into the casing and a water outlet opening through the brush, and a closure 100 for the water outlet of the shaft.

5. The combination of a casing having a water inlet and a water outlet, a brush in the casing and projecting therefrom, said brush having a head which is provided with 105 perforations, a water wheel in the casing between the aforesaid water inlet and outlet, a shaft carrying the brush and the water wheel, a removable gate between the water outlet of the casing and the brush head, the 110 aforesaid shaft being hollow and having a water inlet opening into the casing and a water outlet opening through the brush, and a closure for the water outlet of the casing.

6. The combination of a casing having a 115 water inlet and a water outlet, a brush in the casing and projecting therefrom, said brush having a head which is provided with perforations, a water wheel in the casing between the aforesaid water inlet and outlet, a shaft 120 carrying the brush and the water wheel, a removable gate between the water outlet of the casing and the brush head, the aforesaid shaft being hollow and having a water 125 inlet opening into the casing and a water 130

outlet opening through the brush, a closure for the water outlet of the casing, and a closure for the water outlet of the shaft.

7. The combination of a casing having a fluid pressure inlet and a fluid pressure outlet, a brush in the casing and projecting therefrom, said brush having a perforated head, a fluid pressure motor in the casing between the aforesaid inlet and outlet, a shaft carrying the motor and the brush, said shaft being hollow and having openings into the casing and the brush, a closure for the fluid pressure outlet, and a removable gate between the brush head and the fluid pressure outlet of the casing.

8. The combination of a casing having a fluid pressure inlet and a fluid pressure outlet, a brush in the casing and projecting therefrom, said brush having a perforated head, a fluid pressure motor in the casing between the aforesaid inlet and outlet, a shaft carrying the motor and the brush, said shaft being hollow and having openings into the casing and the brush, a closure for the fluid pressure outlet, a closure for the shaft opening to the brush, and a removable gate

between the brush and the fluid pressure outlet of the casing.

9. The combination of a casing having a fluid pressure inlet and an outlet, a brush having a perforated head extending into the casing, a fluid pressure motor in the casing between the aforesaid inlet and outlet, and operatively connected to the brush, and a removable gate between the motor and the brush head.

10. The combination of a casing having a fluid pressure inlet and an outlet, a brush having a perforated head extending into the casing, a fluid pressure motor in the casing between the aforesaid inlet and outlet, and operatively connected to the brush, a removable gate between the motor and the brush head, and a closure for the aforesaid fluid pressure outlet.

In testimony whereof I affix my signature in the presence of two witnesses.

MARTIN WELLER.
